KNITTED TRUNKS

Filed Sept. 4, 1937

Lewis Silberman Inventor

Felix A. Russell Attorney

UNITED STATES PATENT OFFICE

107,103

DESIGN FOR KNITTED TRUNKS

Lewis Silberman, Brooklyn, N. Y.

Application September 4, 1937, Serial No. 71,484

Term of patent 3½ years

To all whom it may concern:

Be it known that I, Lewis Silberman, a citizen of the United States, residing in Brooklyn, in the county of Kings and State of New York, have invented a new, original, and ornamental Design for Knitted Trunks, of which the following is a specification, reference being had to the accompanying drawing, forming a part thereof.

I claim:

The ornamental design for knitted trunks as shown.

LEWIS SILBERMAN.
